RAIL BOND

William P. Bovard, Mansfield, Ohio, assignor to
 The Ohio Brass Company, Mansfield, Ohio, a
 corporation of New Jersey

Application February 4, 1937, Serial No. 123,950

7 Claims. (Cl. 173—280)

My invention relates to rail bonds for electrically connecting the adjacent ends of rails conducting current.

The object of my invention is to provide a bond having a portion adapted for insertion in an opening or cavity in a portion of the rail, preferably the side of the rail head, and which can be expanded so as to securely engage the side wall of the opening or cavity in the rail.

10 A further object of my invention is to provide a bond which can be easily and simply installed as by means of a hammer.

My invention resides in the new and novel construction, combination, and relation of the 15 parts hereinafter described and shown in the drawing accompanying this specification.

In the drawing:

Fig. 1 is a side view of a single terminal and conductor.

20 Fig. 2 is a longitudinal view in partial section of the terminal and conductor shown in Fig. 1.

Fig. 3 is a sectional view taken on the line 3—3 of Fig. 1.

Fig. 4 is a side view of a pin I use and later 25 describe.

Fig. 5 is a sectional view taken on the line 5—5 of Fig. 3.

Fig. 6 is a modified form of one end of the pin I use.

30 Fig. 7 is a sectional view of a modification of the terminal I use and which corresponds to a section taken on the line 3—3 of Fig. 1.

Fig. 8 shows a bond terminal assembled in a rail prior to the final installation.

35 Fig. 9 is a view showing a terminal completely installed in a cavity in a rail head.

In the preferred embodiment of my invention, I provide a conductor which may be of copper, bronze, or steel. The copper conductor will, of 40 course, give the lowest resistance to the flow of current. The conductor is cut to the length required, and secured to each end is a terminal 2. I have shown the conductor with a terminal at one end only, and bonds are very often so constructed, but the majority of bonds comprise the cable 1 with two terminals 2, one at each end of the conductor.

The terminal 2 comprises a drive portion 3 with a portion 4 projecting therefrom for insertion in the cavity 5 of the rail 6. The portions 3 and 4 may be made of ferrous or non-ferrous metal, the former preferred as for instance, a soft or deformable steel such as forging steel. The member 3 has a projecting sleeve 7.

55 The portion 4 is provided with a channel 8 and

the portions 3 and 7 are provided with a channel 9. These channels intersect. The conductor 1 is positioned in the channel 9 and a pin 10 is secured in the channel 8.

The pin 10 has a shank 11 preferably of uniform diameter and a bifurcated end 12 comprising the spaced prongs 13 forming the slot 14. The pin 10 is made preferably of a heat treated steel such as an alloy steel so treated that it is tough and as hard as or harder than the steel 10 of the terminal portion 4, yet the prongs 13 being bendable as indicated by the dotted lines in Fig. 4.

The pin 10 is also provided with a portion 15 formed with a taper. The portions 11 and 15 of the pin 10 are provided with ribs 16 which cut into the portions of the terminal to prevent rotation of the pin relative to the terminal after assembly.

The pin 10 is also provided with a head portion 17 which has a shoulder face 18 and a tapered end face 19, the latter corresponding with the end wall 20 of the cavity 5 in the rail head.

The terminal portion 4 is provided with an end face 21. Positioned between the faces 18 and 21 25 is a sleeve 22 preferably of copper or other non-ferrous metal. The sleeve 22 may be omitted, if desired, and the metal of the portion 4 extended to the face 18 as shown in Fig. 7.

I prefer the portion of the terminal 22 to be 30 of copper as it is more compressible, easily deformable, expanding in those directions in which it is unrestricted, at the same time it tends to harden as the metal deforms. I find that after the bond terminal has been installed, the portion 22 of the terminal may have even embedded itself into or interlocked with the wall of the cavity.

In constructing my invention, the parts 3 and 4 are forged or pressed from the metal desired 40 preferably soft steel and the channels 8 and 9 formed therein as by drilling. The channel 9 may extend only to the channel 8 or it may extend beyond the channel 8 as shown in Fig. 2. In the latter case the conductor will be locked in place by the bifurcated end of the pin 10 as well as by the compression of the walls of the portions 3 and 7.

The pin is constructed as herein before described and the copper sleeve 22 likewise.

50 The parts having been formed, the cable is first positioned in the channel 9 then the pin is positioned in the channel 8 as far as possible with the sleeve 22 in position on the pin.

The parts are then pressed together axially 55

which forces the pin 10 into final position as shown in Figs. 2 and 3. As the split end of the pin engages with the conductor 1, the ends are spread as shown in Fig. 3 or by the dotted lines 5 in Fig. 4. This interlocks the pin with the drive portion 3 and also interlocks the pin with the conductor 1.

In forcing the parts together the walls of the 10 portions 3 and 7 of the terminal are forced into intimate and close engagement with the conductor 1 thus providing a connection between the parts which will prevent their separation.

The forcing together of the parts into their 15 final position is best brought about by placing the partially assembled parts in suitable dies and subjecting the same to pressure as by means of a stamping or hydraulic press or other apparatus well known to those skilled in the art, thus the size and relation of the parts will be 20 better maintained.

The installation of my invention comprises the drilling of a cavity preferably in the side face of each rail head adjacent the ends of the juxtaposed ends thereof. The depth of the cavity is 25 preferably made somewhat less than the total depth of the parts 4, 22, and 17.

The terminal is then positioned in the cavity which is formed with a side and one end wall as shown in Fig. 8. Pressure is then applied, as by 30 means of a compressor or hammer, to the portion 3 of the terminal.

The force is applied axially thus forcing the terminal tightly against the end wall 20 of the cavity 5 and any further force or pressure applied 35 to the terminal will force the part 4 into the cavity as shown in Fig. 9. In applying the force to the head 3, the member 22 being of relative soft metal and being brought under compression between the faces 18 and 21 (see Fig. 2), the same 40 will be expanded and forced into intimate and binding engagement with the side wall of the cavity 5. Further application of force to the member 3 will cause the portion 4 to shorten thus tending to increase its diameter and force the 45 portion 4 into binding engagement with the wall of the cavity 5.

If the copper sleeve 22 is omitted and the portion 4 of the terminal extended to the face 18 of the pin as shown in Fig. 7, then the entire 50 portion 4 will in time be shortened and simultaneously increased in diameter under force applied to the portion 3 which in turn will cause a binding engagement between the portion 4 of the terminal and the wall of the cavity 5.

55 As previously stated, the parts of my invention may be formed of various metals and combinations thereof, but I prefer to have the pin 10 of as hard a metal and a tougher metal than the other parts, yet not so hard that the prongs 13 will not bend in the assembled operation. It is 60 not my intent that the portions 11 and 15 of the pin shall expand during the installation of the bond.

65 During the installation the portions 3 and 4 may slide upon the pin 10 since the free end of the pin is held by the end face 20 of the cavity 5 and force is applied to the portion 3. This 70 movement of parts during installation tends to tighten the bifurcated end of the pin with respect to the conductor 1 and terminal portion 3.

75 It will be noted that the distances *a* and *b* are equal in Figs. 8 and 9 showing that the extra length of the parts 4 and 22 has been forced into the cavity.

Having disclosed my invention, modifications

will suggest themselves to those skilled in the art; therefore, I wish to be limited only by my claims.

I claim:

1. The combination with a rail having a cavity 5 therein of a rail bond comprising a terminal adapted to be installed in the cavity in the rail and a conductor secured to the terminal, the terminal comprising a drive portion having a channel therein for the reception of the conductor and a second portion projecting from the drive portion and having a channel therethrough which intersects the first channel at substantially right angles thereto, the said second portion being adapted to be inserted in a rail cavity to 10 extend therein short of the end wall of the cavity, a headed pin having a part extending through the last said channel and into the first channel to engage the conductor therein and forming a third portion of the terminal, the said second portion 15 of the terminal having an end face spaced from the head of the pin and a ring of copper forming a fourth portion of the terminal positioned in the said space and encircling the pin, the diameter of the second and the fourth portions and the 20 head of the third portion being equal and the total length of these portions being greater than the depth of the rail cavity, the said second and fourth portions of the terminal being expandable in the rail cavity into binding engagement with 25 the wall of the rail cavity when force is applied to the said drive portion of the terminal.

2. A rail bond comprising a terminal with a conductor secured thereto, the terminal comprising a drive portion having a channel therein for 30 the reception of the conductor and a second portion projecting from the drive portion and having a channel therethrough which intersects the first channel at substantially right angles thereto, the said second portion being adapted to be inserted 35 in a rail cavity to extend therein short of the end wall of the cavity, a headed pin having a part extending through the last said channel and into the first channel to engage the conductor therein and forming a third portion of the terminal, 40 the said pin having a tapered part connecting it to the said first part, the said second portion of the terminal having an end face spaced from the head of the pin and a collar of non-ferrous metal forming a fourth portion of the terminal positioned in the said space and encircling the 45 tapered part of the pin, the second and fourth portions of the terminal being expandable into binding engagement with the wall of the rail cavity when force is applied to the drive portion. 55

3. A rail bond comprising in combination a conductor and a terminal secured thereto, the said terminal comprising a drive portion having means for securing the conductor thereto and a second portion for insertion in a rail cavity, the 60 second portion provided with a channel and a headed pin forming a third portion of the terminal mounted in the channel with the head spaced away from the end face of the second portion, the terminal having a fourth portion of non-ferrous metal positioned between the said end face and the head of the pin and encircling a portion of the pin, means on one end of the pin to secure it in position and permit the said drive and second portions to slide axially relative to the 65 pin to expand the said second portion when force is applied to the drive portion while the other portions of the terminal are positioned in the rail cavity to bind the terminal securely to the rail. 70

4. A rail bond comprising in combination a 75

conductor and a terminal secured thereto, the said terminal comprising a drive portion having means to secure the conductor thereto and a second portion for insertion in a rail cavity, the second portion having a channel therethrough, a pin forming a third portion of the terminal mounted in the channel and contacting with the conductor and having a head to engage the end wall of the rail cavity, the pin being slidable relative to the conductor in an axial direction relative to the said second portion of the terminal when force is applied to the drive portion tending to force the conductor and pin into closer engagement and to expand the end of the second portion of the terminal into close contact with the side wall of the rail cavity.

5. The combination with a rail having a cavity therein of a rail bond comprising a terminal adapted to be installed in a cavity in the rail and a conductor secured to the terminal, the terminal being provided with a drive portion and a second portion adapted to enter and be expanded in the rail cavity, the said second portion having a channel and a pin positioned in the channel, the pin having a bifurcated end engaging the conductor and the other end exposed for contact with the end wall of the rail cavity, the pin adapted to be forced into stronger engagement with the conductor and the said second portion of the terminal adapted to be forced into tight engagement

10

15

20

25

30

with the side wall of the rail cavity when force is applied to the drive portion of the terminal.

6. A rail bond comprising a terminal and a conductor secured thereto, the terminal comprising a drive portion and a second portion adapted to enter and be expanded in a rail cavity, the said second portion having a channel extending axially thereof and a pin of harder material than said second portion mounted in the channel and having one end extending into the said drive portion and engaging the conductor and interlocked with the drive portion to prevent its withdrawal therefrom, means on the pin to interlock with the said second portion of the terminal to prevent relative rotation of the pin and said second portion, the pin having a tapered portion at one end to expand the enclosed end of the second portion of the terminal when the said second portion of the terminal is forced into the rail cavity.

10

15

7. A rail bond terminal for installation in a rail cavity comprising a part adapted to receive a conductor and a second part to be inserted within the rail cavity, the latter part of the terminal having a separately formed central portion of relatively softer material than the other portion, and adapted to be expanded into holding engagement with the side wall of the rail cavity when the said second part is forced into the rail cavity.
